FUEL AND AIR FEEDING MEANS FOR LIQUID FUEL BURNING APPARATUS, AND MOUNTING FOR SAID MEANS AND ASSOCIATED ELEMENTS

Wilbur A. Schultz, Lakewood, and Malcolm W. Patrick, Hudson, Ohio, assignors to Perfection Stove Company, Cleveland, Ohio, a corporation of Ohio

Application March 21, 1951, Serial No. 216,774

7 Claims. (Cl. 158—91)

1

This invention pertains, generally, to the class of liquid fuel burning apparatus, and more particularly to improved means for feeding fuel and a limited amount of air to the combustion space of a type of such apparatus characterized by a natural draft pot type burner. The invention has to do, also, with a mounting for said fuel and air feeding means and associated elements.

The fuel and air feeding phase of the present invention represents a further development of the scheme for feeding fuel and air to the combustion space of apparatus of the aforesaid class, originally disclosed in an application of Lee S. Chadwick et al., filed September 21, 1948, Serial No. 50,312, which has matured into Patent No. 2,614,618 of October 21, 1952, and elaborated upon in an application filed by Marc Resek et al., June 16, 1950, Serial No. 168,524. Said Patent No. 2,614,618 and copending application Serial No. 168,524 are assigned to the same assignee as the present application. In each of these former cases, the apparatus was of the forced draft type in that the air supplied thereto was of considerable quantity and for combustion purposes.

The fundamental purpose of this invention, like that of its predecessors, is to provide a liquid fuel combustion apparatus that is efficient, economical and satisfactory in the burning of so-called catalytic fuels, and that will function without the formation or deposition of carbon or other residue upon any part of the apparatus where the presence of such would adversely affect the operation.

It has been found that, in order to successfully handle liquid fuels of the aforesaid type, it is necessary that the fuel be maintained at a relatively low temperature during its passage to the point of its admission to the combustion space. However, upon being admitted to said space, the fuel must be rapidly transformed into a state suitable for burning, which generally means that it must be converted from liquid to gas and immediately mixed with a suitable amount of air. It is essential, on the other hand, that the actual combustion take place relatively remote from the point where the fuel enters so that the fuel discharge means, or nozzle, will be kept at a comparatively low temperature in order to prevent the formation of carbon thereon.

Another object of the invention is to so arrange the air conducting means with respect to the region of combustion that the combustion air is preheated a limited amount before reaching the point of its mixture with the fuel, thereby to better advance vaporization of the latter.

2

Another object of the invention is to so relate the fuel nozzle to the parts surrounding it (which parts define the fuel entrance to the combustion space) as to insure against the fuel contacting such parts or being deposited thereon, which would be conducive to carbon formation.

Although obstruction of the fuel entrance to the combustion space is highly unlikely unless fuels of a very inferior quality are used, it is a further object to provide reliable means for draining overflow fuel from the region of the nozzle to a suitable place of disposal, in case the entrance should become clogged.

A still further and important object of our invention is to provide a unitary assembly, or so-called "package," that includes, according to the present disclosure, the fuel and air feeding means; an air impeller or blower and its driving motor; various devices that are constituents of an electrical system for automatically controlling the operation of the combustion apparatus and which system desirably involves an electrical igniter, and a mounting by which the foregoing parts are carried and which includes closure means for an opening of the walled structure that encloses the combustion space and through which opening extend the fuel and air feeding means and, in the present instance, the electrical igniter.

Our invention is especially intended for use with pot type burners, for which reason we have so illustrated it in the drawings; and by virtue of its self-contained or "package" characteristic, it may readily be applied to practically any prevailing pot type burner without much, if any, modification, and thus adapt such apparatus to the satisfactory burning of catalytic fuels.

The foregoing and other objects and advantages are attained in the embodiment of the invention illustrated in the accompanying drawings, wherein like reference characters designate like parts in the several views.

In the drawings, Fig. 1 represents a central vertical section, from front to rear, through the unitary assembly or "package" incorporating our improved fuel and air feeding means, and through the adjacent portion of a liquid fuel burning apparatus to which the assembly is applied; Fig. 2 is a front elevational view, and Fig. 3 a plan view of the parts shown in Fig. 1, certain of the parts being in section; Figs. 4 and 5 are somewhat enlarged sectional details taken on the line A—A of Fig. 1, looking, respectively, in the direction of the arrows 4 and 5; Fig. 6 is a perspective view of the mounting that carries the

elements of the fuel and air feeding means and associated electrical devices, and a portion of which serves as a closure for an opening that leads into the combustion space of the apparatus, and Fig. 7 is a diagram of an electrical control system for the apparatus, certain elements of which are carried by the mounting.

Our invention is herein disclosed as applied to a liquid fuel burner of the bowl or pot type, and in Figs. 1, 2 and 3 a portion of the burner bowl is shown, the same being designated, generally, by the reference numeral 1. A relatively large opening 2 occupies the front portion of the peripheral wall 3 of the bowl, and it is surrounded by an outwardly extending flange about which fits the inner end of a neck 4. The neck is secured to the wall 3, desirably by welding, as indicated at 5, and at its forward end the neck is flared outwardly to provide a flange 6. The bottom wall 7 of the burner bowl is slightly dished and is shown as provided with a central sump 8, and within the relatively large opening of the annular top wall 10 of the bowl is secured the reduced lower end of an upwardly divergent throat member 11, shown as terminating in a flat marginal portion 12 that may constitute the bottom wall of a combustion chamber. The throat member 11 is provided with openings 15 and the peripheral wall 3 of the bowl 1 with openings 16, for the admission of air to the combustion space of the apparatus, such space being constituted of the interior of the burner bowl and the combustion chamber above (not shown).

As will be readily understood, the combustion space communicates with a suitable flue or chimney, and in the present instance the apparatus operates on natural draft, in contra-distinction to the forced draft apparatus disclosed in each of the above-identified applications.

Turning now to a detailed description of the present invention, 20 denotes, generally, a mounting, shown in perspective in Fig. 6. The major portion of the flat rear wall 21 of the mounting constitutes a closure for the opening 2 of the burner bowl, and it is adapted to be applied to the flange 6, with a gasket 22 of suitable packing material interposed between the latter and the opposed area of said wall. Dowels 23, that project forwardly from the flange 6, extend through aligned holes in the gasket 22 and wall 21. Also projecting forwardly from the flange 6 are threaded studs 25 that are engaged through holes in the gasket and occupy notches 26 in the wall 21. Wing nuts 28 are applied to the studs 25 for drawing the parts firmly together. By reason of this simple means of attachment, the assembly may be easily and quickly applied to and removed from the combustion apparatus. The forward end of an outer air tube or cup-like shell 30 occupies an opening on the wall 21 and said end is secured to the surrounding portion of the wall, desirably by welding. An inner tube or shell 33, which is of less diameter but somewhat longer than the outer shell 30, is arranged within the latter in substantially concentric relation thereto. The end wall 35 of the outer shell is imperforate, while the corresponding wall 36 of the inner shell, which is spaced from the wall 35, is provided with a relatively large opening 37.

40 denotes an annular member or nozzle guide which is shown as cylindrical and of reduced diameter at its lower end. The smaller end of the guide occupies an opening in the peripheral wall of the outer shell 30, to which wall said end

is welded or otherwise secured; and the adjacent end of the portion of greater diameter fits within a hole in the peripheral wall of the inner shell 33 and is secured to said wall in similar fashion.

It will be observed that the previously mentioned opening 37 is spaced nearer the top than the bottom of the inner shell, and disposed transversely of said shell, some distance forwardly of the nozzle guide 40, is a dam 44, that rises to about the height of the lower side of said opening 37, the dam being suitably sealed, as by welding, to the peripheral wall of the inner shell. Thus, an overflow basin is provided within the inner shell about the nozzle guide 40; and any fuel overflowing into said basin will be conducted, by a drain tube 45, to the lower portion of the burner bowl 1, or to some other suitable place of disposal. In the present instance, as in the construction disclosed in the Resek et al application above referred to, a trough surrounds the lower portion of the peripheral wall of the burner bowl. The trough herein is designated 34, and upon liquid fuel attaining an abnormally high level in the bowl, it will overflow through the openings 16 of the bottom row in the peripheral wall 3 and be carried away by a pipe 35.

46 designates a fuel supply pipe that is extended inwardly through a notch in the forward end of the shell 33 and thence rearwardly to where it has connection, through a union 47 and an elbow 48, with a fuel nozzle that is designated, generally, by the reference numeral 50. The nozzle guide 40 has an axial passage enlarged at its upper end to provide an annular shoulder or seat 51, and at a distance below said shoulder the passage is downwardly convergent. Removably nested within the upper end of the nozzle guide, so as to rest upon the shoulder 51, is the relatively deep disc-like part or flange 52 of the nozzle 50, the tubular tip of the nozzle depending axially from said flange and terminating at its lower end in a frusto-conical portion that is disposed in spaced concentric relation to the convergent wall portion of the passage of the nozzle guide 40. Opening into the upper end of said passage are a plurality of air holes 53 in the flange 52. The nozzle is provided with an axial port 55 that is counterbored and threaded at its upper end for the reception of the threaded lower end of the elbow 48. Above its frusto-conical portion, the nozzle 50 is bored transversely to provide lateral openings, and below said openings the nozzle is slotted in line with said openings, thus imparting a bill-like appearance to the lower or fuel discharge end of the nozzle. This particular nozzle forms a part of the subject matter of the above mentioned application, Serial No. 168,524, and, as pointed out in that case, it affords highly satisfactory fuel discharge, and so directs the fuel as to prevent contact thereof with the nozzle guide. This is highly important as otherwise residue and carbon would collect and build up about the fuel inlet under the influence of the high temperatures prevailing within the combustion space during burner operation.

Rigidity is imparted to the outer end of the inner tube or shell 33 by a suitable number of spacers 58 that are interposed between the shells 30 and 33 in the approximate plane of the wall 21 of the mounting 20, said spacers being suitably fastened to either or both of the shells. Telescoped over the forward end of the inner shell 33 is the peripheral flange of a reducing collar 59, said flange having a relatively wide

notch to accommodate the fuel pipe 46 and permit limited turning with respect thereto. A bayonet joint connection between the collar and shell 33 is provided by an L-shaped slot 60 in said peripheral flange, and a pin 61 that extends from the shell 33. Fitted within and suitably fastened, as by welding, to a forwardly projected flange of the collar 59 is the tubular discharge extension 63 of the scroll casing 64 of an air impeller blower designated, generally, by the reference numeral 65. The fan or rotor 66 of the impeller or blower is driven by an electric motor 68, the housing of which is shown as attached to and solely supported by the impeller or blower casing 64.

Carried by the wall 21 of the mounting 20, is an arcuate deflector 69, located adjacent the upper portion of the outer end of the shell 30. As will be observed from Figs. 1 and 2, said deflector extends forwardly from the wall 21 to about the vertical plane of the outer end of the shell 33, and thence inwardly into close proximity to the body portion of the collar 59. As a consequence, that portion of the output of the air impeller or blower that passes through the opening 37 and forwardly between the shells 30 and 33, and raised to a relatively high temperature during its circulation, will be deflected downwardly away from the adjacent electrical devices that might otherwise become unduly heated.

70 denotes an electrical igniter of the embedded sheathed type, similar in this respect to the one disclosed in the aforesaid application, Serial No. 168,524. It is, generally speaking, in the shape of a hairpin loop, and has forwardly extending terminal portions 70^a engaged through holes in a plate 71 to which said terminal portions are welded or otherwise secured. Said plate 71, in turn, is attached, by screws 72, to the wall 21 of the mounting 20, over an opening 73 through which the igniter 70 may be emplaced or withdrawn. Accordingly, the igniter is made a part of the unitary assembly or "package" hereinbefore referred to. Forwardly of the plate 71, the terminal portions of the igniter are equipped with binding posts 70^b. The inner end of the igniter is preferably inclined downwardly and rearwardly from the terminal portions toward the bottom wall 7 of the burner bowl. Applied to said inner end of the igniter is a baffle 74 in the form of a relatively wide channel or trough against which the fuel impinges as it drops from the nozzle 50.

Secured to and projecting forwardly from the wall 21 of the mounting 20 is a bracket 75 that supports a flow-control or shut-off valve 76, with the outlet end of which the fuel supply pipe 46 has connection through an elbow 77 and its associated fittings. Connected to the opposite or inlet end of the valve is a pipe 78 that leads from a suitable source of supply of liquid fuel (not shown). The valve 76 carries a solenoid 79 by which the valve is operated.

Provisions are made for attaching to the mounting 20 various electrical devices that are constituents of an electrical control system by which the operation of the combustion apparatus is rendered automatic. A wiring diagram of a control system suitable for use with the present apparatus, constitutes Fig. 7 of the drawings. Another example of such a system is disclosed in application Serial No. 168,524, already referred to.

In the present instance a so-called Micro-switch 80 is supported directly above the forward end of the inner shell or tube by a bracket 81. This

bracket has a base flange 86 that is welded or otherwise secured to the wall 21 of the mounting 20. The actuator of the Micro-switch 80 has an adjustable operative connection, through a screw 82, with the forward end of a bimetal strip 83 that extends rearwardly along the top side of the shell or tube 33 and is connected at its rear end to the outer shell 30 by screws 84, a spacer 85 being interposed between the strip and said shell. The aforesaid deflector 69 is notched to accommodate the forward end of the bimetal strip 83, as will appear from Figs. 1 and 2.

Side walls 87 and 88 extend forwardly from the ends of the relatively wide upper portion of the wall 21, and shown as sustained by the side wall 88 is a relay 90. Also carried by this side wall, forwardly of the relay 90, are brackets 92 that support a terminal block 95. These electrical devices, as already mentioned, and as will more fully appear hereinafter, are constituents of an electrical control system, as are also the igniter 70, motor 68 and solenoid 79.

A cover 97 is shown as applied to the mounting 20, and the same is preferably constructed of sheet metal. At its ends it overlies the top and front edges of the walls 87 and 88, and is flanged downwardly and inwardly along said respective edges exteriorly of said walls, and is held in place by screws 98.

30 The combustion apparatus wherewith we have shown our invention associated, may be incorporated in a water heater, or it may be employed as a space heater. The control system schematically illustrated in Fig. 7 is adapted to either. It 35 includes a master thermostat 100, which is subjected to the temperature of the medium to be heated, as will be readily understood. A conductor 101 is represented as leading from the positive or hot side of a source of electrical energy (not shown), which source may be the usual house circuit of 115 volts, for example. 102 designates a safety switch, usual in such control systems, which acts automatically to open the control circuit and shut down the apparatus in case the apparatus becomes overheated or a short circuit occurs. The conductor 101 leads to the master thermostat 100, the finger of which is arranged to engage a contact 103 from which a conductor 105 leads to the blade of the Micro-switch 80, which has been previously described as carried by the mounting 20. As will be remembered, the switch has adjustable operative connection, through the screw 82, with the free end of the bimetal strip 83, and when the parts whose temperature affects the action of said strip are cold, the Micro-switch 80 is closed, or, in other words, the blade thereof is in engagement with a contact 108. A conductor 109 leads from this contact to a junction designated 110; and a conductor 111, in turn, leads from said junction to one end of the winding of the relay 90. This relay, as will be recalled, is also carried by the mounting 20. The other end of its winding has connection with a return conductor 112 that leads to the negative or ground side of the source of electrical energy.

The relay 90 is of the double pole, double throw type. It is represented as including two blades 117 and 118 that are connected by a link 119 to cause them to act in unison, the blade 117 being illustrated in the diagram as constituting the armature of the relay. When the relay is de-energized, as represented in Fig. 7, the blade 117 is out of engagement with a contact 120, while the blade 118 is in engagement with a contact 121. The contact 120 is placed in electrical connec-

tion, through a conductor 125, with the previously mentioned conductor 105, between the contact 103 of the master thermostat 100 and the Micro-switch 80. A conductor 126 leads from the contact 121 to the junction 127 of said conductor with a conductor 130. This latter conductor has connection with the first mentioned conductor 101 and, through it, with the positive or hot side of the source of electrical energy. The conductor 130 leads to one of the connections of the motor 68 of the air impeller or blower 65, and from the other connection thereof a conductor 131 leads to the return conductor 112.

From the junction 110, a conductor 133 leads to the pivoted end of the blade 117 of the relay 90, while the corresponding end of the other blade 118 is placed in electrical connection with one of the binding posts of the igniter 70 through a conductor 135, a conductor 136 leading from the other binding post of the igniter to the return conductor 112. Current is also carried from the junction 110, by a conductor 137, to one end of the coil of the solenoid 79 that operates the fuel valve 76, the opposite end of said coil being electrically connected, through a conductor 138, with the return conduit 112. It would be well to explain that the fuel valve 76 is biased toward closed position, as by means of a spring, and that it is opened by the solenoid 79 when the latter is energized.

We have described the control system as operating on the line voltage of a house circuit. Obviously a transformer may be employed, the primary of which would be connected across the house circuit, while the two ends of its secondary coil would represent, respectively, the positive and negative sides of the source of electrical energy, and wherewith the respective conductors 101 and 112 would be connected. In such a case, electrical devices would be selected that would operate on the reduced voltage.

We have also shown the motor 68 of the air impeller or blower as being connected to the positive side of the circuit ahead of the master thermostat 100. Accordingly, the impeller or blower will operate at all times that the system is in connection with a source of electrical energy. This constant running of the impeller or blower has the advantage of keeping the fuel and air feeding means relatively cool during burner operation. Also, through the above described circuit, including the blade 118 of the relay 90, and the igniter 70, said igniter is maintained at fuel igniting temperature as long as the relay 90 is de-energized.

As previously pointed out, the Micro-switch 89 is closed when the bimetal strip 83 is relatively cool. This presupposes that there is no fire in the combustion apparatus. Accordingly, when the master thermostat 100, responsive to a drop in temperature of the medium to be kept heated, operates to close the circuit (in the present instance by the finger of the thermostat swinging into engagement with the contact 103), current flows through conductor 105, Micro-switch 80, conductor 109, junction 110 and conductor 111 to the winding of the relay 90, the current continuing on to the source through the return conductor 112. Upon the relay thus being energized, it will swing the blade 117 into engagement with the contact 120 and the blade 118 away from the contact 121. Consequently current reaches junction 110 not only through the path including the Micro-switch 80, but also through a "holding" circuit represented by conductor 125, blade 117 and conductor 133; thereafter the relay 90 and the solenoid 79 are no longer dependent on the circuit through the Micro-switch 80 for their current supply since sufficient current reaches junction 110 through the "holding" circuit to energize these elements.

Therefore, the conditions at the moment are as follows: the temperature to be controlled is below a predetermined value for which the master thermostat is set; said thermostat has functioned to close the circuit through the Micro-switch 80 that initially supplies current to the relay 90 and the solenoid 79; the relay 90 operates, firstly, to establish the "holding" circuit that will continue to supply current to the relay 90 and to the solenoid 79 after the Micro-switch 80 opens, and, secondly, to simultaneously interrupt the flow of current to the igniter 70; the fuel valve 76 is held open by the solenoid so that fuel, with air from the continually operating impeller or blower 65, is discharged into the combustion space, and is vaporized and lighted by the igniter 70 that remains hot enough to perform these functions, notwithstanding the fact that flow of current thereto has been interrupted.

With the combustion apparatus thus set in operation, the temperature of the burner parts will rise and cause the bi-metal strip 83 to warp in the direction to open the Micro-switch 80, this action requiring a brief period of time—approximately two minutes in practice. Operation of the apparatus will continue, however, by virtue of the "holding" circuit, until the temperature of the medium rises enough to cause the master thermostat 100 to open the circuit at the contact 103. This opening of the circuit effects immediate de-energization of the relay 90, and of the solenoid 79, the former, incidentally, re-establishing the ignition circuit, and the latter allowing the valve 76 to close and shut off the supply of fuel to the apparatus. As a consequence, the fire will go out and the burner parts excepting the igniter 70 will cool off and permit the bimetal strip 83 (in the space of about two minutes, for example) to resume its former condition and close the Micro-switch 80, thus placing the system in readiness for the next operation.

We claim:

1. Fuel and air feeding means for liquid fuel combustion apparatus, said means comprising a first cup-like shell in the form of a tubular member which is entirely closed at one end and is fully open at the other, said shell being arranged with its axis substantially horizontal, a second similar cup-like shell of substantially lesser cross sectional area than the first disposed within the first shell in spaced relation to the walls of the latter, the second shell having an opening in the end thereof that corresponds to the bottom of the cup and which end is contiguous to the closed end of the first shell, the opposite end of the second shell being its outer end, the interiors of the shells communicating through said opening so that the space enclosed by the second shell and the space between said shells provide a circulating air passageway, each shell having an aperture in its lower side that is aligned with the aperture of the other shell, an annular member connecting the shells about the apertures thereof, fuel conducting means extending into the second shell and including a nozzle at its inner end that is disposed within said annular member in spaced relation to the portion of said annular member that surrounds the nozzle, the space within the annular member being in communication with

said circulating air passageway, and an air impeller including a casing having an outlet connected to the outer end of the second shell in such manner that the entire output of the impeller is discharged into the second shell and so that a part of said output escapes through said annular member and the remainder thereof proceeds through said passageway.

2. Fuel and air feeding means for liquid fuel combustion apparatus, said means comprising a first cup-like shell in the form of a tubular member which is entirely closed at one end and is fully open at the other and that is arranged with its axis substantially horizontal, a second similar cup-like shell of substantially lesser cross sectional area than the first projecting into the first shell in spaced relation to the walls of the latter, the second shell having an opening in the end thereof that corresponds to the bottom of the cup and which end is contiguous to the closed end of the first shell, the opposite end of the second shell extending a distance beyond the open end of the first shell, means adjacent the open end of the first shell for supporting the second shell in fixed relation to the first shell, the interiors of the shells communicating through the aforesaid opening so that the space enclosed by the second shell and the space between the shells provide a circulating air passageway, each shell having an aperture in its lower side that is aligned with the aperture of the other shell, an annular member connecting the shells about the apertures thereof, fuel conducting means extending into the second shell and including a nozzle at its inner end that is disposed within said annular member in spaced relation to the portion of said member that surrounds the nozzle, the space within the annular member being in communication with said circulating air passageway, and an air impeller including a casing having an outlet so connected to said opposite end of the second shell that said second shell provides the sole support for the air impeller and receives the output thereof so that a part of said output passes through said annular member and the remainder thereof proceeds through said passageway.

3. Fuel and air feeding means for liquid fuel combustion apparatus, said means comprising a first cup-like shell in the form of a tubular member which is entirely closed at one end and is fully open at the other and that is arranged with its axis substantially horizontal, a second similar cup-like shell of substantially lesser cross sectional area than the first disposed within the first shell in spaced relation to the walls of the latter, the second shell having an opening in the end thereof that corresponds to the bottom of the cup and which end is contiguous to the closed end of the first shell, the opposite end of the second shell being its outer end, the interiors of the shells communicating through said opening so that the space enclosed by the second shell and the space between said shells provide a circulating air passageway, spacers interposed between the peripheral portions of the shells adjacent the open end of the first shell, each shell having an aperture in its lower side that is aligned with the aperture of the other shell, an annular member connecting the shells about the apertures thereof, fuel conducting means extending into the second shell and including a nozzle at its inner end that is disposed within said annular member in spaced relation to the portion of said member that surrounds the nozzle, the space within the member being in communication with said circulating air

passageway, and an assembly comprising an air impeller and its driving motor attached to the outer end of the second shell, whereby the second shell provides the sole support for said assembly, said air impeller including a casing having an outlet so connected to the outer end of the second shell that the output of the impeller is delivered to the aforesaid circulating air passageway so that a part of said output passes through said annular member and the remainder thereof proceeds through said passageway.

4. Fuel and air feeding means for liquid fuel combustion apparatus, said means comprising a first cup-like shell in the form of a tubular member which is entirely closed at one end and is fully open at the other and that is arranged with its axis substantially horizontal, a second similar cup-like shell of substantially lesser cross sectional area than the first arranged within the first shell in spaced relation to the walls of the latter, the second shell having an opening in the end thereof that corresponds to the bottom of the cup and which end is contiguous to the closed end of the first shell, the opposite end of the second shell projecting beyond the open end of the first shell, the interiors of the shells communicating through said opening so that the space enclosed by the second shell and the space between said shells provide a circulating air passageway, each shell having an aperture in its lower side that is aligned with the aperture of the other shell, an annular member connecting the shells about the apertures thereof, fuel conducting means extending into the second shell and including a nozzle at its inner end that is disposed within said annular member in spaced relation to the portion of said member that surrounds the nozzle, the space within the annular member being in communication with said circulating air passageway, a reducing collar connected at its larger end to said opposite end of the second shell, and an air impeller including a casing having an outlet extension so connected to the smaller end of said collar that the output of the impeller is delivered to the aforesaid circulating air passageway so that a part of said output passes through said annular member and the remainder thereof proceeds through said passageway.

5. Fuel and air feeding means for liquid fuel combustion apparatus, said means comprising a mounting adapted to be disposed in a substantially vertical plane across an opening leading into the combustion space of such apparatus, said mounting having an aperture, a first cup-like shell in the form of a tubular member which is entirely closed at one end and is fully open at the other having its open end connected to the mounting about said aperture, a second similar cup-like shell of substantially lesser cross sectional area than the first projecting into the first shell and arranged in spaced relation to the walls of the latter, the end of the second shell corresponding to the bottom of the cup having an opening and which end is contiguous to the closed end of the first shell, the interiors of the shells communicating through said opening so that the space enclosed by the second shell and the space between said shells provide a circulating air passageway, each shell having an aperture in its lower side that is aligned with the aperture of the other shell, an annular member connecting the shells about the apertures thereof, means sustaining the end of the second shell that is adjacent the open end of the first shell in fixed relation to the mounting, fuel conducting

means extending into the second shell and including a nozzle at its inner end that is disposed within said annular member in spaced relation to the portion of said member that surrounds the nozzle, the space within the annular member being in communication with said circulating air passageway, and an air impeller including a casing having its outlet so connected to the end of the second shell adjacent said mounting that said second shell provides the sole support for the air impeller and receives the output thereof so that a part of said output passes through said annular member and the remainder thereof proceeds through said passageway.

6. For use with liquid fuel burning apparatus comprising a walled structure enclosing a combustion space and having a side opening leading into said space; a mounting including a wall portion adapted to serve as a closure for said opening, said wall portion having an aperture, a first cup-like shell in the form of a tubular member which is entirely closed at one end and is fully open at the other and that is adapted to extend into the combustion space and having its open end attached to the wall portion about said aperture, and a second similar cup-like shell of substantially lesser cross sectional area than the first projecting into the first shell in spaced relation to the walls thereof, the second shell having an opening in the end thereof that corresponds to the bottom of the cup and which end is contiguous to the closed end of the first shell, the interiors of the shells communicating through said opening so that the space enclosed by the second shell and the space between the shells provide a circulating air passageway, each shell having a hole in the lower side thereof that is in alignment with the hole of the other shell, a nozzle guide secured to the shells about the holes thereof, a fuel nozzle positioned within the guide, the nozzle and guide defining an air passage leading from the interior of the second shell so as to receive air from the aforesaid circulating air passageway and which passage continues about the discharge end of the nozzle, a fuel supply pipe extending into the second shell and connected to the nozzle, and an air impeller including a casing having an outlet so connected to the outer end of the second shell that said second shell provides the sole support for the air impeller and receives the output thereof.

7. Fuel and air feeding means for liquid fuel combustion apparatus, said means comprising a mounting adapted to be disposed in a substantially vertical plane across an opening leading into the combustion space of such apparatus, said mounting having an aperture, a first cup-like shell in the form of a tubular member which is entirely closed at one end and is open at the other and which has its open end connected to the mounting about said aperture, a second similar cup-like shell of substantially lesser cross sectional area than the first projecting into the first shell and arranged in spaced relation to the walls of the latter, the second shell having an opening in the end thereof that corresponds to the bottom of the cup and which end is contiguous to the closed end of the first shell, the interiors of the shells communicating through said opening so that the space enclosed by the second shell and the space between said shells provide a circulating air passageway, each shell having an aperture in its lower side that is aligned with the aperture of the other shell, an annular member connecting the shells about the apertures thereof, means sustaining the end of the second shell that is adjacent the open end of the first shell in fixed relation to the mounting, fuel conducting means extending into the second shell and including a nozzle at its inner end that is disposed within said annular member in spaced relation to the portion of said member that surrounds the nozzle, the space within the annular member being in communication with said circulating air passageway, an air impeller including a casing having its outlet so connected to the end of the second shell adjacent the mounting that said second shell provides the sole support for the air impeller and receives the output thereof, and a cover applied to the mounting and overlying the air impeller.
